INJECTOR BURNER FOR AUTOGENOUS
METAL WORKING

Felix Damm, Dusseldorf, Germany

Application June 2, 1934, Serial No. 728,797
In Germany January 2, 1932

4 Claims. (Cl. 158—27.4)

I have filed applications in Germany, January 2, 1932 and August 23, 1932; Netherlands, May 2, 1934; France, May 4, 1934 and England, May 7, 1934.

This invention relates to injector burners, more particularly for metal working, such as welding or cutting burners. Known injector burners for these purposes have the defects that they are not economical in operation and that the supply of the combustible gas during working does not remain constant since, owing to the heating of the burner tip, the quantity of gas admixed is reduced. To obviate these defects, so-called high pressure or constant pressure burners have been proposed. But even with such burners, the throttling of the combustible gas supply taking place during the working is not overcome, and no economical utilization of the mixture is attained.

The object of this invention is to provide an injector burner in which a disadvantageous throttling of the gaseous mixture during the working is eliminated and in which the welding output is considerably increased, without additional consumption of combustible gases being necessary.

According to the invention, the improved burner is formed with a mixing chamber for the oxygen and fuel gas mixture ahead of the oxygen nozzle, which chamber communicates by means of special channels or the like with the outer air. Furthermore there is provided ahead of the first mixing chamber, a second mixing chamber with one or more hollow spaces abutting thereon which act in such manner that the mixture has a suction effect at the mouths of the hollow spaces. Thus, air is added to the fuel gas mixture inside the burner, whereby an increased economical utilization of the mixture of fuel gas and oxygen is attained, since by the replacement of a small portion of the cylinder oxygen from the air, the outlet velocity, and thus the welding output of the burner, is improved without a greater consumption of fuel gases. In addition to increasing the outlet velocity, the flame cone is furthermore improved by the addition of air, this more favorably influencing the welding output than with the use of a pure acetylene and oxygen flame. For example, in a first injector stage, fuel gas is entrained or drawn by oxygen and in a second injector stage, air is entrained by a mixture of fuel gas and oxygen. This arrangement presents the advantage that in on stage is an explosive mixture entrained, so that back-firing in the gas pipe is absolutely avoided.

In order that the mixture may act with a suction effect at the mouths of the hollow spaces, a

certain partial vacuum is produced in the latter during the operation of the burner, which compensates for the throttling of the gaseous mixture and consequently makes the supply of fuel gas uniform.

The improved burner may also be provided with only a single mixing space which is in communication with one or more closed hollow spaces in such manner that the mixture has a suction at the mouthpieces of the hollow spaces. This arrangement applies to burners in which merely the uniformity of the supply of fuel gas is of importance.

In the accompanying drawing:—

Fig. 1 is a longitudinal cross-section of one construction of burner according to the invention, and

Fig. 2 is a partial longitudinal section to a larger scale of a further construction of burner.

In the construction shown in Fig. 1, the oxygen, which flows out of the cylinder at a certain pressure, passes to the housing 1 of the burner through the pipe connection 2 into the valve 3 which can be opened and closed or regulated by means of a handwheel 4. A conduit 5 leads from the valve 3 to an oxygen nozzle 6, from which oxygen flows into the mixing chamber 7. At this point, an injector action takes place in an annular space 8 surrounding the nozzle 6. The combustion gas passes through a pipe connection 9 on the housing 1 into a cut-off and regulating valve 10 which is controlled by a handwheel 11, and then through a conduit 12 into an annular space 13 which is in communication with the annular space 8. By means of the injector action of the nozzle 6, the combustion gas also passes into the mixing chamber 7. The mixing proportion of the two gases herein is determined by the holes in the oxygen nozzle 6 and in an inlet nozzle 14 of the mixing chamber 7, as also by their position in respect to each other. The mixing chamber 7 is surrounded by an annular space 15 which communicates through holes 16 with the outer air and through a second nozzle 17 with the mixing chamber 7. From the mixing chamber 7, the mixture flows through the second nozzle 17 into a second mixing chamber 18. During the passage of the gas from 17 to 18, an injector action again takes place in the annular space 19 surrounding the nozzle 17, by means of which atmospheric air is entrained through the holes 16 into the space 19 and into the second mixing chamber 18, in which there is now produced a mixture of oxygen, fuel gas and air. This mixture flows through a further nozzle 20 to the tip 21 of the burner, an injector

action again taking place in an annular space 22 surrounding the nozzle 20, by means of which injector action a partial vacuum is constantly maintained in a second adjacent space 23. If 5 necessary, a number of hollow spaces 23 may be provided.

If, in operation, a throttling action occurs, due to the front part of the burner being highly heated, this operates primarily on the vacuum 10 space 23 and only to a small extent upon the nozzle 20. Here, however, the mixing proportion supplied by the injector remains constant, since the throttling can at the most only act on the gaseous mixture and not, as with simple injector 15 burners, on the fuel gas supply. By means of the arrangement described, an increased security against back-firing of the burner is attained since, in the first place, the ignition velocity of the mixture remains constant with the ratio of the mixture 20 and, secondly, should for any reason back-firing nevertheless take place, this will be extinguished in the evacuated space 23 before reaching the nozzle 20. When, in consequence of very 25 great heating of the burner tip, such considerable back pressures occur that the partial vacuum in the subsidiary space 23 is decreased to such an extent that the back pressures act further on the rear injector stage, then both the air and the fuel gas suction injector stages are affected. Should 30 the partial vacuum in chambers 15 and 23 be so reduced that the back pressure throttles the oxygen from the nozzle 6 the vacuum produced by the flow from said nozzle in 13 will be likewise reduced so that even with the most highly heated burners, 35 the ratio of the mixture may be maintained at a constant ratio.

In the case of a welding burner having a copper tip with a hole of 1.7 mm. and a consumption of 500 litres per hour, the consumption for a 40 neutrally adjusted flame is 500 litres per hour of fuel gas and 500 litres per hour of oxygen, giving a total consumption of 1000 litres per hour, which is equivalent to an outlet velocity of 119 metres per second.

45 With the burner according to the invention, if, for example, sufficient air is to be added in the second stage to provide 10% of the oxygen, the result is that the burner in the second stage must draw in 250 litres of air per hour. The hourly 50 consumption of the burner is consequently 500 litres of fuel gas, 450 litres of oxygen (from the cylinder), and 250 litres of air containing 50 litres of oxygen, or altogether 1200 litres of mixture, which is equivalent to an outlet velocity of 147 55 metres per second.

Fig. 2 shows a construction in which the supply of atmospheric air to the burner is dispensed with. With this burner also, an oxygen nozzle 6 is provided for the inlet of oxygen into the mixing 60 chamber 7 and furthermore an annular space 8 on the nozzle 6 for the injector-like suction of the fuel gas out of a space 13, a second nozzle 17 with an annular space 19, and a secondary space 15 or a number of such spaces abutting on to the said 65 annular space 19. The mixture flows from the nozzle 17 into the burner tube 24. Here, by the injector action at the annular space 19, a partial vacuum is maintained in the space 15 surrounding the mixing space 7. Consequently, the same action 70 takes place as with the burner according to the first construction, the gaseous mixture remaining constant even with the greatest heating of the burner tip and flame back-firing into the suction chambers being prevented.

75 Having now particularly described and ascer-

tained the nature of my said invention and in what manner the same is to be performed, what I claim is:—

1. In a burner of the kind described, an elongated casing having a chamber therein provided at its forward end with a constricted outlet passage, a mixing chamber fitted in said casing and projecting into the first mentioned chamber, a nozzle fitted on the forward end of the mixing chamber in alinement with the constricted passage, said mixing chamber and nozzle being spaced from the wall of the casing to provide an annular chamber, a fourth chamber having a constricted port in communication with the rear end of the mixing chamber, an oxygen nozzle 10 located in the fourth chamber in spaced relation to the wall thereof, means to supply oxygen to said nozzle, and means to supply fuel gas to the fourth chamber outside said nozzle.

2. In a burner of the kind described, an elongated casing having a chamber therein provided at its forward end with a constricted outlet passage, a mixing chamber fitted in said casing and projecting into the first mentioned chamber, a nozzle fitted on the forward end of the mixing 20 chamber in alinement with the constricted passage, said mixing chamber and nozzle being spaced from the wall of the casing to provide an annular chamber, a fourth chamber having a constricted port in communication with the rear end 25 of the mixing chamber, an oxygen nozzle located in the fourth chamber in spaced relation to the wall thereof, means to supply oxygen to said nozzle, and means to supply fuel gas to the fourth chamber outside said nozzle, said casing having air ports therein opening into the space around 30 said first nozzle whereby to admit air thereto.

3. In a burner of the kind described, an elongated casing having a chamber therein provided at its forward end with a constricted outlet passage, a mixing chamber fitted in said casing and projecting into the first mentioned chamber, a nozzle fitted on the forward end of the mixing chamber in alinement with the constricted passage, said mixing chamber and nozzle being spaced 40 from the wall of the casing to provide an annular chamber, a fourth chamber having a constricted port in communication with the rear end of the mixing chamber, an oxygen nozzle located in the fourth chamber in spaced relation to the wall 45 thereof, means to supply oxygen to said nozzle, means to supply fuel gas to the fourth chamber outside said nozzle, said fourth chamber constituting a primary mixing chamber for fuel and oxygen, said casing having air ports therein 50 opening into the space around said first nozzle whereby to admit air thereto, a third mixing chamber located in the forward part of the casing and leading from said constricted passage, a nozzle fitted on the forward end of said third 55 mixing chamber, said last mixing chamber and nozzle being spaced from the wall of the casing to provide an annular vacuum chamber, said casing having a constricted passage at its forward end, and a burner tip in communication with the last mentioned constricted passage.

4. In a burner of the kind described, an elongated casing having a chamber therein provided at its forward end with a constricted outlet passage, a mixing chamber fitted in said casing and projecting into the first mentioned chamber, a nozzle fitted on the forward end of the mixing chamber in alinement with the constricted passage, said mixing chamber and nozzle being spaced from the wall of the casing to provide 70

an annular chamber, a fourth chamber having a constricted port in communication with the rear end of the mixing chamber, an oxygen nozzle located in the fourth chamber in spaced relation to the wall thereof, means to supply oxygen to said nozzle, and means to supply fuel gas to the fourth

chamber outside said nozzle, said mixing chamber having the space therein increasing in area from the inlet end to the outlet end and the nozzle of said mixing chamber having its bore decreasing from its inlet to its outlet.

FELIX DAMM.
